PACKAGE FOR MEDICAMENT TABLETS
OR THE LIKE

Heinz Grunewald and Karl Heinz Lindner, Berlin, Germany, assignors to Schering AG., Berlin, Germany

Filed July 30, 1964, Ser. No. 81,073

Term of patent 14 years

(Cl. D58—2)

FIG. 1 is a top plan view of a package for medicament tablets or the like embodying our new design;

FIG. 2 is a front elevational view;

FIG. 3 is a bottom plan view; and

FIG. 4 is a side elevational view, the opposite side being substantially the same in appearance.

We claim:

The ornamental design for a package for medicament tablets or the like, substantially as shown and described.
